H. J. HALE.

Seed-Drill Teeth.

No. 22,870.

Patented Feb. 8. 1859.

UNITED STATES PATENT OFFICE.

HENRY J. HALE, OF INDIANAPOLIS, INDIANA.

IMPROVEMENT IN ARMS OF BROADCAST-SEEDING MACHINES.

Specification forming part of Letters Patent No. **22,870**, dated February 8, 1859.

To all whom it may concern:

Be it known that I, HENRY J. HALE, of Indianapolis, in the county of Marion and State of Indiana, have invented a new and useful Improvement in Broadcasting Grain-Sowers, of which the following is a full and exact description, reference being had to the accompanying drawings and the letters of reference marked thereon.

Figure 1 is a perspective, and Fig. 2 a sectional, view of the arm of a broadcasting grain-sower, which by being revolved casts the grain by centrifugal force.

A is a pitman designed to operate the lever B, which operates the slide or valve C. The arm has an extension beyond the slide C, which is hinged at D and adjusted and held at any desired angle of elevation or depression by means of the slotted segments and set-screws E E.

The construction of the extension is as follows: The bottom plate is hinged at D, while the opening F, which allows the bending of the arm, is lined or guarded with sheet metal in such a manner as to cause no obstruction to the free passage of grain through the arm. The top of the opening F is closed by sheet metal, which, by bending and sliding in the groove G, keeps the passage through the arm open and complete while bending the required angle of elevation or depression. The bottom of the slide or valve C, when closed, rests upon a piece of gum-elastic, which is fitted in the bottom of the arm at H to prevent the closing of the valve from crushing the grain.

J is a valve designed to regulate the amount of grain discharged, and is operated by the

set-screw K, which is held, when adjusted, by the guard L.

The operation is as follows: The arm, being constructed so that in revolving it describes a circle of four feet at the extreme end of the same, is placed upon a carriage having two wheels four feet in diameter, which gives motion to the arm or revolves it in a similar manner to that employed by other broadcasting machines or arms which sow grain by centrifugal force. The valve C is operated similarly to the operation of valves in other broadcasting grain-sowers for discharging the grain at the proper time.

By simply bending the extension of the arm and elevating and depressing the same I have varied the cast of grain from fifteen to sixty feet in width. The amount of grain sown is regulated by the set-screw K and valve J. The advantage of this arrangement is seen in the fact that grain may be sown when the air is still to the extent of sixty feet in width of land or cast, while when the wind is blowing it may be sown by depressing the extension of the arm, thereby contracting the extent of the cast and causing the grain to be sent to the ground with greater force.

What I claim, and desire to secure by Letters Patent, is—

The combination and arrangement of the segments E E and hinge D, when constructed and arranged as and for the purposes set forth.

HENRY J. HALE.
